UNITED STATES PATENT OFFICE.

WILLIAM THURBER, OF CHICAGO, ILLINOIS, ASSIGNOR TO SINCLAIR LAUNDRY MACHINERY CO., OF CHICAGO, ILLINOIS, A CORPORATION OF ILLINOIS.

IRONING OR BOSOM BOARD.

No. 846,433.

Specification of Letters Patent.

Patented March 5, 1907.

Original application filed November 19, 1904, Serial No. 233,434. Divided and this application filed August 6, 1906. Serial No. 329,437.

To all whom it may concern:

Be it known that I, WILLIAM THURBER, a citizen of the United States, of Chicago, in the county of Cook and State of Illinois, have 5 invented certain new and useful Improvements in Ironing or Bosom Boards; and I do hereby declare that the following is a full, clear, and exact description thereof, reference being had to the accompanying drawings, and to the letters of reference marked thereon, which form a part of this specification.

This invention relates to improvements in ironing or bosom boards over which is fitted 15 a shirt or like garment and which supports the front or bosom of the garment while being ironed.

The invention consists in the matters hereinafter set forth, and more particularly 20 pointed out in the appended claims.

Among the objects of the invention is to improve the construction and operation of the ironing - surface so as to facilitate the pressing of shirt fronts or bosoms having 25 a central or otherwise disposed plait or buttons, to provide an improved guard for protecting the operator from the pins by which the top cloth of the ironing-surface is detachably fixed in place, and to provide an 30 improved construction and arrangement whereby a number of ironing-boards of varying sizes may be interchangeably used on a single support.

As shown in the drawings, Figure 1 is a top 35 plan view of an ironing-board embodying my improvements, partially broken away to show the construction of the ironing-surface. Fig. 2 is a bottom plan view thereof. Fig. 3 is a transverse section of the board, taken on the 40 line 3 3 of Fig. 1 and showing the support of said board. Fig. 4 is a longitudinal section taken on the line 4 4 of Fig. 1. Fig. 5 is an end view of the board and its support. Fig. 6 is a detail illustrating the arrangement for 45 removably fixing the pin-guard frame in place.

As shown in said drawings, A designates as a whole what is hereinafter termed the "ironing or bosom board." It is a composite 50 structure embracing a suitable plate or support constituting the foundation thereof to give rigidity thereto and superposed yielding

layers of suitable material over which is stretched a cloth constituting the ironing-surface proper. The ironing-board is herein 55 shown as supported on a spider-like frame B, which in turn is mounted on a plate or board B', this arrangement being like that shown in my prior application for United States Letters Patent, Serial No. 233,434, filed November 19, 1904, for improvements in ironing-machines, of which this application is a division.

The base or foundation of the ironing-board proper comprises a generally flat metal 65 plate A', on the under surface of which are formed longitudinal and transverse bearing members a' a'', that rest on upwardly-facing horizontal bearing-surfaces of the support B. The said bosom-board is detachably secured 70 to the support B in such manner that bosom-boards of varying dimensions may be interchangeably used with the single support B. For this purpose the said support is provided at its front and rear ends, respectively, with 75 screw-threaded studs b b', and said studs are provided with beveled heads b² b³, respectively, which engage undercut notches a³ a⁴, formed on the under face of the plate A'. The under face of said plate is cut away adjacent to said notches to permit said heads to properly engage the notches. As herein 80 shown, the head b² of the stud b may be fixed permanently in place, while the head b³ of the stud b' is cut away to provide a straight 85 portion b⁴ on the side thereof opposite its beveled portion. When the stud b' is rotated, therefore, its beveled portion is disengaged from its associated notch. When this occurs, the forward end of the ironing-board 90 is free to be raised, and by shifting the board forwardly it may be released from the head of the rear stud, and thereby detached from its support. The said forward stud b' is provided with a handle b⁵, by which the stud may 95 be rotated to disengage it from and engage it with the undercut recess a⁴ in the manner stated.

A feature of my improvements relating to the ironing-surface of the board embraces a construction which provides an area or section of the ironing-surface which is more yielding than other parts of the surface, such superyielding area or section being designed

to support during the pressing operation the part of a shirt front or bosom provided with a plait or a row of buttons. This arrangement is such that such raised parts of the bosom may sink into the superyielding section or area, thereby avoiding the pressing of the buttons into the material or bosom or unduly compressing the plait or plaits and causing them to adhere to the bosom.

10 Referring now to the illustrated construction of the composite board and the manner of producing the ironing-surface having the characteristics referred to, the same is made as follows: The base-plate A' is provided at 15 its sides and forward end with a marginal rim A², Figs. 3 and 4, and is provided on its upper face with a longitudinally-disposed recess or depression A³, in which is mounted a strip A⁴ of yielding material, such as soft rubber, of a thickness to project above the upper face of said plate. Resting on the upper surface of the plate at each side of said central strip and between the same and the side rims or flanges A² are wider strips A⁵ of 20 yielding material, which may also be made of rubber and harder than the said central strip. The upper surfaces of said side strips are flush with or in the same plane as the upper surface of the central strip A⁴. Overlying 25 said strips or sections of rubber A⁴ A⁵ is a soft yielding layer A⁶, which may consist of a number of thicknesses of cotton flannel or like material. Laid over said layer A⁶ is a cloth A⁷, the outside surface of which constitutes the exposed ironing-surface of the board. The said surface cloth extends at 30 its margins over the margins of the plate A' and is attached to the board at the two sides and the front end margins thereof by means 35 of pins a⁸ a⁹, extending laterally outwardly from said end and sides of the board. The surface cloth A⁷ at the end of the board which is formed to provide the collar-recess A⁸ is folded downwardly over the end 40 margins of the board and upwardly against the under face of the board and is attached thereto at each side of the collar-recess by means of pins a⁸ a⁹, Fig. 5, extending downwardly from said lower face of the board.

45 In the arrangement herein shown the central strip A⁴ is made thicker than the side sections A⁵ by reason of its being placed in said central depression of the plate. It is only essential, however, that said central strip be 50 made of a material possessing greater yieldability than the side sections and sufficiently thick to receive raised portions of the shirt front or bosom, as before stated. The location of the central strip within the depression 55 A³ is structurally advantageous, however, for the reason that it is thereby held more firmly in place, and, further, because the side strips or sections A⁵ are held in place between the side rims A² of the base-plate and 60 the central strip A⁴.

Surrounding the end and side margins of the board is a pin-guard frame C, herein shown as made of angle-bar cross-section, the said guard-frame being removably supported on the board in such manner that it may be 70 readily detached from and attached thereto. To this end the horizontal flanges c of the angle-bars composing the frame lie upon the upwardly-facing marginal parts of the board, while the vertical webs c' of said bars depend 75 outside of the attaching-pins a⁵ below the level of the latter. This manner of supporting the frame holds it from lateral movement on the board. It is held from endwise movement on the board by means of bolts or studs 80 D, extending laterally from the board and engaging inclined notches c², Fig. 6, formed in pieces c³, fixed in any suitable manner to the side members of said frame. The rear ends of the vertical webs of the side arms of 85 the guard-frame are turned inwardly, as shown in Figs. 1, 2, and 5, to avoid sharp projecting parts at the inner end of the board, the presence of which are objectionable.

The pins a⁶ on the under face of the plate 90 A', by which the cloth at the neckband end of the board is fixed in place, are covered by guard-plates E, located one at each side of the neckband-recess and fixed thereto by screws e or in any other suitable manner. 95 The said guard-plates E are provided at their outer side margins with upwardly-directed flanges e', which extend upwardly between the rear ends of the arms of the guard-frame C and the sides of the board, the flanges of 100 said guard-frame arms being recessed or cut away, as shown at c⁴, Fig. 1, to receive said flanges of the guard-plates.

The ironing-board described may be employed in connection with an ironing-machine such as is shown in my aforesaid pending application, Serial No. 233,434, or said improvements may be applied to an ironing or bosom board designed for hand-ironing. The clamping devices by which the neckband and shoulder of the garment being ironed, as well as the tension device by which tension is brought on the bosom of said garment, are not herein shown, inasmuch as any suitable form of clamping and tension mechanism 105 may be employed.

I claim as my invention—

1. An ironing-board having an ironing-surface provided with a yielding support, said yielding support comprising a strip or area which is made of a material more yielding than the other parts of said support, for the purpose set forth.

2. An ironing-board having an ironing-surface provided with a yielding support, 125 said yielding support comprising a longitudinally-disposed part which is made of a material more yielding than the other parts of said support, for the purpose set forth.

3. An ironing-board comprising a base- 130

plate, an ironing-surface and a yielding body interposed between the base-plate and the ironing-surface including a longitudinal central part made of a material more yielding than the side portions thereof.

5 4. An ironing-board comprising a base-plate, an ironing-surface, and an interposed yielding support consisting of two side sections and a centrally-disposed strip, which latter is made of a material more yielding than the side sections.

10 5. An ironing-board comprising a base-plate provided with a central longitudinal depression, a soft strip of yielding material 15 within said depression, and sections of relatively harder material on the plate, one at each side of the central strip, said central strip being made thicker than, and flush at its upper surface with said side sections, and 20 an ironing-surface cloth thereon.

25 6. An ironing-board comprising a base-plate, a rubber support thereon comprising two side sections and a centrally-disposed strip, which latter is more yielding than the side sections, a layer of yielding material resting on said support, and a surface cloth thereon.

7. An ironing-board comprising a base-plate provided with a central longitudinal depression, an ironing-surface cloth, and an 30 interposed yielding support consisting of a strip of yielding material within said depression and sections of relatively harder material one at each side of the central strip, said central strip being thicker than and flush at 35 its upper surface with said side sections, and said base-plate being provided with rims or flanges, between which and the central strip, said side sections are held in place.

8. The combination with an ironing-board 40 and its support, said board being provided on its under face with undercut notches, studs mounted in said support and provided with beveled heads adapted to enter said notches, one of said studs being rotatable to 45 release it from its associated undercut notch.

In testimony that I claim the foregoing as my invention I affix my signature, in the presence of two witnesses, this 25th day of July, A. D. 1906.

WILLIAM THURBER.
